CLAIM

The ornamental design for a droplet sorter, as shown and described.

DESCRIPTION

FIG. 1 is a front elevational view of a droplet sorter showing our new design; and,

FIG. 2 is a left side elevational view of our ornamental design for a droplet sorter of FIG. 1. Note that a right side elevational view of our ornamental design for a droplet sorter is a mirror image of the left side elevational view depicted in FIG. 2.

Any broken line in the drawings is an illustration of environmental structure which is hereby disclaimed, forming no part of our design.
